UNITED STATES PATENT OFFICE.

JAMES WAYLAND, OF NEWARK, NEW JERSEY.

PNEUMATIC SEMAPHORE-SIGNAL.

SPECIFICATION forming part of Letters Patent No. 447,988, dated March 10, 1891.

Application filed July 3, 1890. Serial No. 357,617. (No model.)

To all whom it may concern:

Be it known that I, JAMES WAYLAND, a citizen of the United States, residing at Newark, in the county of Essex and State of New Jersey, have invented certain new and useful Improvements in Pneumatic Semaphore-Signals; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

The object of this invention is to provide an automatic train-signaling device of reduced cost of construction—one having a more compact and simple arrangement of parts—and to indicate to the conductor or engineer the proximity of a previous train, as will be more fully set forth.

The invention consists in the improved pneumatic signaling apparatus and in the arrangements and combinations of parts, substantially as will be hereinafter set forth, and finally embodied in the clauses of the claim.

Referring to the accompanying drawings, in which like letters and numerals indicate corresponding parts in each of the several figures, Figure 1 is a vertical section showing the device in connection with the railway. Fig. 2 is a detail view of a certain catching or holding lever. Fig. 3 is a detail of a fulerumed bracket for the same. Fig. 4 is a detail plan of a certain valve. Fig. 5 is a plan of a support for a stationary piston. Figs. 6 and 7 are respectively a plan and section on line *x* of a connecting-piece which joins a certain cylinder with a piston or connecting-rod. Fig. 8 is a detail plan of the guides for said piston or connecting-rod, and Fig. 9 is a plan of the head of said piston. Figs. 10 and 11 are enlarged sectional views of the mechanisms for operating the semaphore detached from the standard or post and shown in different positions, and Fig. 12 is a similar view showing a varied construction.

In said drawings, *a* indicates a hollow post, which may be of wood or metal or a combination of the two, and *b* indicates a semaphore, which is pivoted at *c*, Figs. 1, 10, and

11, and weighted, as at *e*, so that the weight nearly counterbalances that of the semaphore, there being a slight difference, however, sufficient to allow the semaphore to gravitate automatically. The weighted arm *e* may be glazed, as at *e'*, with red glass, so that at night when the said arm drops on account of the passage of a train the glass will pass in front of a lantern or white light, and thus show to the engineer or conductor of the following train the red danger-signal, indicating the proximity of an advance train. Within the said hollow post *a* are bearings *g g* for a longitudinal piston or connecting-rod *h*, which latter extends vertically from the foot or lower end of the post, where it engages or is engaged by a lever *i*, adapted to receive the pressure of the track as the train passes over it or of the wheels of the train direct, as indicated in broken line in Fig. 1. The lever *i* is fulcrumed near the track and has its longer arm engage the vertical piston or connecting-rod, so that a slight depression of said track will give considerable vertical movement to the said piston or connecting-rod, as will be understood. A spring *j* may be employed to cushion the movement of the rod *h*, due to inertia, after having been suddenly thrown by the lever. At a point near the upper end of the piston or connecting-rod is arranged a fixed bracket or bearing *k* for a stationary head *l*, adapted to operate in connection with a cylinder *m*, arranged to reciprocate in connection with the piston or connecting-rod *h*. The said head *l* is preferably of cylindrical or round form and is in that event screwed into a female thread *k'*, formed in the bearing or bracket *k*. The movable cylinder *m* is preferably secured to the piston or connecting-rod *h* by means of a coupling-head *n*, provided with ears *o o*, carrying a pivot *p*, on which the piston-rod is secured, the said coupling-head *n* being riveted, as at *q*, or otherwise secured to downwardly-extending arms *r* of the cylinder, as shown more clearly in Figs. 10 and 12. A valve *s* is provided, which is adapted to allow of a sudden inflow of air to the chamber *t* of the cylinder. The said valve may have its seat on the fixed head *l*, as in Figs. 1, 10, and 11, being held in proper normal relation thereto by a spring *u*,

or the said valve may have its seat on the cylinder, as in Fig. 12, in which case the cylinder-head or end plate *m'* is perforated to allow of the desired inflow of air to the cylinder. From said cylinder-chamber a small opening *w'* allows of a slow escape of air from said cylinder. This I have shown both in the valve *s* in Figs. 1, 10, and 11 and in the head *l* in Fig. 12. It may be formed in any other suitable position. The outflow through said small opening may be regulated and controlled by a valve *w*, having suitable bearings at the end of said opening, where it may be easily manipulated or adjusted.

15 By means of the movable cylinder working on a fixed piston-head I am enabled to secure a simple construction and one cheaply manufactured. Expensive guides or ways for regulating the movement of the parts are dispensed with, and the chamber may be filled with air from the outer atmosphere automatically or by the movement of the walls forming the chamber.

In connection with the movable cylinder is arranged a vertical rod 2, which may be secured to the upper end or head of the cylinder in any suitable manner. The said rod 2 may be solid, as in Fig. 12, or tubular or hollow, as in Figs. 10 and 11, in the latter case the said rod being arranged in telescopic connection with an upper rod 3, connecting with a crank or lever 4, secured to the pivot *c* of the semaphore *b*. When the rod 2 is solid, it is arranged in line with the said upper rod 3, or so as to engage the end of the same. An upward movement of the cylinder and rod 2 connected therewith is adapted to cause the said rod to engage the upper rod or a bearing 5 and to throw the same upward, so as to turn the crank or lever 4 and semaphore, as will be understood. When the rod 3 is at the upper limit of its stroke, it is caught by a catch 6, preferably a lever pivoted upon a bracket or bearing 7, formed or secured upon the interior of the post or standard *a*. By means of the catch the said rod 3 and the semaphore connected therewith are held a limited period of time, which is regulated by means of the escape-valve *w*. As the lower rod 2 descends a bearing 8 thereon engages the arm 9 of the lever and throws the latter from catching relation with the bearing of the rod 3, as will clearly be understood upon reference to Fig. 10.

55 In operating the device the lever *i* on the passage of a train over the track throws the rod *h* and the movable cylinder connected therewith upward, opening the valve *s*, because of the otherwise impervious connection and arrangement of the cylinder and head *l*, on which said cylinder slides. The air rushes through the perforations or openings 10 as the cylinder-chamber *t* enlarges, and upon the closing of the valve *s* at the end of 65 the stroke given by the lever *i* is held against a certain amount of pressure about equal to

the weight of the rod 2 and its attachments. The upward movement of the rod *h* and cylinder and its rod 2 throws the rod 3 upward to a point where it will be caught, as above described. The pressure on the air in the chamber *t* causes it to escape through the small opening or vent *w'*, and as it thus flows outward the cylinder and rod 2 are allowed to slowly descend, and when the bearing 8 engages the lever 9 the latter is thrown from catching engagement and the rod 3 immediately drops to the position indicated in Fig. 11, carrying with it the semaphore. By adjusting the screw of the valve *w* the outflow of air from the cylinder is regulated and the length of time of holding the semaphore in its position indicative of danger is increased or diminished at will.

I am aware that other modifications or variations than those specifically provided for can be made.

Having thus described the invention, what I claim as new is—

1. In a railway-signal, the combination, 90 with the semaphore and air-receptacle *m*, of separate or independent rods 2 and 3 and a catch operable to hold rod 3 and to be thrown from holding engagement by rod 2, substantially as and for the purposes set forth.

2. In a railway-appliance, the combination, with a part *b* to be operated and a rod 2, adapted to move under an impulse given by the railway-train, of a rod 3, movable independent of the said rod 2 and connected to said part *b*, means for holding said part *b* stationary while the said rod 2 is returning to a normal position after the said impulse given by the railway-train, and means on said rod 2 for releasing said holding means, substantially as set forth.

3. In a railway-signal, the combination, with the semaphore, of a rod 2, adapted to be moved vertically under the impulse of the passing train, an independent rod 3, connected to said semaphore and provided with a bearing 5, and a lever adapted to engage said bearing and to hold said rod 3 from gravitating, the said rod 2 being provided with means adapted to engage said lever and release the same from holding engagement, substantially as and for the purposes set forth.

4. In a railway-appliance, two movable rods arranged in line, one provided with a bearing to receive a catch and the other a bearing to trip said catch, and said catch extending into positions to engage said bearings, whereby when the upward movement of one of said rods will throw the other upward the latter will be caught and held until the gravitation of the other rod will cause its bearing to trip the catch and allow the first rod to gravitate, substantially as set forth.

5. In a railway-appliance, the combination, with the part *b* to be operated, of a vertical rod 3, connected with and operating the same and provided with a catch-bearing 5, a rod 2,

movable vertically under the impulse given by the passing train and provided with a bearing 8, and a pivoted lever 6, adapted to engage the said bearings 5 and 8, substantially as and for the purposes set forth.

5 6. In a railway-signal, in combination, the semaphore *b*, pivoted at *c*, crank 4, rod 3, operating the same and having bearing 5, a rod 2 in line with said rod 3, but movable independent thereof, and having a bearing 8, a lever 6, adapted to enter into holding engagement with said bearing 5 and to be thrown from such engagement by the bearing 8, and means, substantially as described, for forcing 10 said rod 2 under the impulse given by the passing train, substantially as set forth.

15 7. In a railway appliance, the combination, with the vertically-movable rod 2, an independent movable rod 3, and catch, of an air-receptacle having a movable part connected with said rod 2 and means for introducing air to said receptacle, means for allowing the slow escape of said air and gravitation of said movable part and rod connected therewith, and means operable by said gravitating parts to release said catch, substantially as and for the purposes set forth.

20 8. In a railway appliance, the combination, with the part 3 to be operated by the passing train, of a catch to hold said part stationary, a pneumatic receptacle having a movable part connecting with the railway and adapted to be operated by the passing train to cause an inflow of air to said receptacle and at the same 25 time to force the said appliance or part 3 into engagement with said catch, and a vent adapted to allow an outflow of air from said receptacle and the gravitation of the movable parts, the gravitating parts being adapted to 30 engage the catch, whereby the part 3 is released to return automatically to an initial position, substantially as set forth.

35 9. In combination, semaphore *b*, crank 4, rod 3, having bearing 5, independent rod 2, having bearing 8, catch 6, air-receptacle having a movable part *m*, connecting with said rod 2, valve allowing an inflow of air to said receptacle, a vent allowing a slow exit, and means for forcing the air into said receptacle, substantially as and for the purposes set forth.

40 10. In a railway appliance, the combination, with the part to be operated and a catch to hold the same in position when thrown from the normal position by the passing train, of a device adapted to be operated upon by the passing train to throw said part to be operated into engagement with said catch and to gravitate immediately thereafter, the said device 45 vice having a suitable projection to engage said catch and release the same from said part to be operated to allow the same to return to a normal position, substantially as set forth.

45 11. In combination with the lever *i* and rod *h*, having a cylinder secured at the upper end thereof, with arms *r* and head *n*, a fixture

5 *k*, having the head *l*, on which the said cylinder works, a valve to allow a rapid inflow of air and a valve to allow a slow outflow of air, a rod 2, fixed to and working with the cylinder, having a bearing 8, a rod 3, adapted to be operated by the rod 2 and to be separated therefrom and having a bearing 5, and a catch adapted to be engaged by said bearings 8 and 5, substantially as set forth.

70

75

10 12. In a railway appliance, substantially as set forth, the rod 2, connected with the railway and adapted to be operated by the passing train, said rod having a bearing 8, in combination with a rod 3, having a bearing 5, and a catch adapted to hold said rod 3 in a raised position until released by engagement with the bearing 5, substantially as set forth.

15 13. In a railway appliance, a rod 2, connected with the railway and having a bearing 8, a rod 3, arranged telescopically therein and having a bearing 5, and a catch adapted to be engaged by said bearing, substantially as set forth.

20 14. In a railway appliance, a rod 3, adapted to be held in a stationary position, a rod 2, adapted to be operated by the passing train and to operate said rod 3 to raise it to its stationary position, means for holding said rod 3 in its stationary position, and means connected to said rod 2 to release the said rod 3, said parts being combined substantially as set forth.

25 15. In a railway appliance, the combination, with a rod 3 adapted to be forced to an elevated position by the movable portion of a pneumatic receptacle, of a catch for holding said rod in said elevated position, a vent adapted to allow the gravitation of said movable portion, and a releasing bearing controlled by said movable portion, whereby the catch may be released from holding engagement with the elevated rod at a desired point of its gravitation, substantially as set forth.

30 16. In a railway appliance, the combination, with a semaphore or other railway appliance or device adapted to be moved from one position to another and to be held at said other position, of a rod 2, adapted to be operated by the passing train in connection with the movable portion of a fluid-receptacle, a catch controlled by said rod for holding said semaphore stationary, a vent to allow a return movement of the said movable portion of the fluid-receptacle, and means for regulating the flow of fluid from said vent, whereby the said return movement may be controlled with reference to time, substantially as set forth.

35 17. In a railway appliance, the combination, with the rod 3, adapted to be raised and held stationary, of a catch for holding the same, a fluid-receptacle having a movable part controlled by the passing train and controlling the rod 3 to raise the same and a releasing bearing to disengage the catch from holding relation to the said rod 3, a valve to allow an inflow of fluid to said receptacle, and a vent

40 45 50 55 60 65 70 75 80 85 90 95 100 105 110 115 120 125 130

allowing a slow outflow, substantially as set forth.

18. In a railway appliance, the fixture *k*, a threaded head screwed thereto, and a cylinder 5 movable on said head and connected to the railway to be operated by the passing train, said parts being arranged and adapted to operate substantially as set forth.

19. In a railway appliance, a cylinder having arms *rr*, in combination with connections

for operating said cylinder under the power transmitted from the passing train, substantially as set forth.

In testimony that I claim the foregoing I have hereunto set my hand this 2d day of 15 July, 1890.

JAMES WAYLAND.
